COMBINED YARN PACKAGE CLASSIFIER AND SCALE

James A. King, Sr., Greensboro, N.C., assignor to
J. A. King & Co.

Filed Oct. 15, 1974, Ser. No. 514,476

Term of patent 14 years

Int. Cl. D10—04

U.S. Cl. D10—88

FIG. 3

FIG. 2

FIG. 1

FIG. 1 is a front elevational view of a combined yarn package classifier and scale showing my new design, the rear being substantially plain and unornamented;

FIG. 2 is a left side elevational view thereof, the right side being substantially similar thereto; and

FIG. 3 is a top plan view thereof, the bottom being plain and unornamented.

I claim:

The ornamental design for a combined yarn package classifier and scale, as shown.
